KNOCKDOWN PICNIC TABLE

John C. La Rue, Bainbridge, Ohio

Application May 6, 1941, Serial No. 392,073

7 Claims. (Cl. 155—124)

This invention relates to the art of collapsible tables and the like, especially picnic tables.

The object of this invention is to devise an efficient and dependable supporting structure for the table and seat members, all of which can be conveniently collapsed and packed into substantially flat form and readily set up for use.

Another object is to devise such a structure that can also be arranged for use as a bed, by virtue of the reversibility of parts.

A further object is to provide a convenient canopy-supporting means in connection with the structure when employed either as a picnic table or as a bed.

More specifically, the object is to devise a strong structure that comprises a minimum number of parts of unitary form, comprising tubular elements, and that are not apt to get out of order or become broken and that can be collapsed into substantially flat condition for storage or transportation.

Other objects will appear from the following description and claims when considered together with the accompanying drawing.

Fig. 1 is a perspective view of my improved structure when employed as a picnic table with a canopy-supporting structure embodied therein;

Fig. 2 is a perspective view of the same structure when employed as a bed, the canopy-supporting frame being here omitted;

Fig. 3 is an enlarged detail view of one of the T-connections at the end of the transverse tubular members, when employed either as a table or bed without the canopy-supporting frame; and

Fig. 4 is a view corresponding with the showing of Fig. 3 except that here the canopy-supporting frame is included.

It is to be understood that the present form of disclosure is merely for the purpose of illustration and that there might be devised various modifications thereof without departing from the spirit of the present invention as herein set forth and claimed.

In the present form of construction, the entire frame consists of metal tubing of comparatively small diameter. This frame comprises the transverse tubular member 1 which has welded thereto, as a permanent part of the same, the inverted U-shaped tubular portion 2 which is located at about mid-length of the member 1. This inverted U-shaped member is intended to support the table member 3 which may be of wood; and the side portions of the member 1, at the two sides of the table, are intended to support the seat members 4 which may also be made of wood.

The inverted U-shaped portion 2 will, of course, afford proper elevation for the table with respect to the elevation of the seats.

At each end of each member 1 there is permanently attached a T-connector member 5 with the duplicate screw-threaded portions 5a and 5b which extend upwardly and downwardly for the purposes to be explained. For instance, when the frame is employed for supporting a table and seats, as in Fig. 1, the lower projections of the T-connectors are adapted to receive the screw-threaded ends of the inverted T-shaped legs 6. When the table is set up, as shown in Fig. 1, the legs 6 are rotatably adjusted so that their feet 6a occupy positions extending lengthwise of the table; and when the table is knocked down, the legs may be rotatably adjusted so that the feet 6a will occupy positions in the same plane as the inverted U-shaped portion 2 which in turn is in the same plane as the upwardly and downwardly extending portions of the T-connectors 5.

As a means of holding the seat members 4 in position, each one is provided with a hole 7 near the outer end corner thereof so as to fit over the projection of the T-connector 5, and a flanged screw-threaded member 8 is engaged in the T-connector projection, the flange thereof having effective holding engagement with the adjacent portion of the seat member, in each case, as indicated in Fig. 3. Any suitable means may be employed for securing the table member or members in place, if deemed necessary or advisable. It is, of course, more essential that a securing means be provided for holding the seat members in place. It is to be understood that the table itself may comprise a plurality of boards instead of a single table member, if so desired.

Instead of the form of securing means 8 for holding the seat members in place, there might be adopted the upright tubular members 9 which have screw-threaded engagement with the T-connector at each corner as a part of the supporting means for a canopy C, the screw-threaded washer 8' serving to hold the seat members in place in this assembly. At the upper ends of the members 9 there are permanently attached the T-connectors 10, to the inner ends of which are removably secured by screw-threaded engagement the transverse tubular members 11, while at the outer ends thereof I have provided the screw-threaded extensions 12 so as to ensure that the canopy C will afford ample protection to the seats. The canopy C, as indicated, extends over the top of the superstructure just described and may be readily removed therefrom; in fact the

entire canopy-supporting structure may be readily taken down and collapsed into compact form for either storing or shipping with the rest of the structure.

Whenever desired, the same structure may be converted into a means for supporting a bed or the like, as indicated in Fig. 2. For this purpose, the legs are entirely removed, the unitary members 1 and 2 are inverted and the legs 6 are then screwed into the T-connector so as to support the same with the continuously transversely extending tubular supporting members 1, as indicated in Fig. 2, upon which there may then be placed the table and seat members 3 and 4 side by side and in the same plane for use as a bed or the like. If so desired, the canopy-supporting structure may be added thereto by applying the uprights 9 to the upwardly projecting portions of the T-connectors, in the same manner as indicated in Fig. 1.

If so desired, the table and seat members may be formed of foldable hinged sections and any suitable means may be employed for holding them in rigid extended condition during their use upon the supporting structure. It is to be understood, also, that in addition to the table and seat supporting units at the two ends there may be employed an intermediate duplicate unit or units, if deemed necessary or advisable.

As compared with the many prior collapsible or knockdown tables and seats, my present structure is reduced to a comparatively few unitary parts which are also of comparatively small bulk but which at the same time are sufficiently strong and dependable by virtue of the structural nature and form; and my structure possesses also the further advantage of being collapsible very readily into a comparatively small space, since all of the parts may occupy substantially flat condition. The reversibility of parts, permitting use of the supporting frame as a bed or the like, constitutes another important feature of my invention.

What I claim is:

1. A knockdown table and seat comprising a plurality of duplicate seat-supporting members, a table-supporting inverted U-shaped member attached to each of said seat-supporting members at about mid-length thereof, an inverted T-shaped leg having rotatably adjustable connection with each end of each seat-supporting members so that the T-head may occupy position at ninety degrees to the seat-supporting member for supporting the same or be turned to dispose the T-head into the plane of the table and seat-supporting members so as to lie in substantially the same plane with said inverted U-shaped members, whereby said members may be stacked in substantially flat condition when the table and seat members are removed, flat seat and table members therefor, and means for removably securing said seat members in position at opposite sides of the table.

2. A knockdown table and seat comprising a plurality of duplicate straight seat-supporting members of tubular form, a table-supporting inverted U-shaped member attached to each of said seat-supporting members at about mid-length thereof, a T-connector member attached to each end of each of said seat-supporting members and having upwardly and downwardly extending screw-threaded portions, an inverted T-shaped leg having screw-threaded connection with each of said downwardly extending portions so that the T-head may occupy position at

ninety degrees to the seat-supporting member for supporting the same or be turned to dispose the T-head in the plane of the table and seat supporting members so as to lie in substantially the same plane with said inverted U-shaped member, whereby said members may be stacked in substantially flat condition when the table and seat members are removed, flat seat and table members therefor, said seat members having

5 apertures to engage over said upwardly extending portions, and screw-threaded means for engagement with said upwardly extending portions for securing said seat members in place.

3. A knockdown table and seat comprising a plurality of duplicate straight seat-supporting members, table-supporting members, means attaching a table-supporting member in parallel arrangement above each of said seat-supporting members, a T-connector member attached to each end of each of said seat-supporting members and having upwardly and downwardly extending duplicate screw-threaded portions, an inverted T-shaped leg adapted for screw-threaded engagement with either of said portions of said 15 T-connector member, flat seat and table members, and means for removably attaching said seat members to the other of said portions in each instance, said seat and table members being of an aggregate width corresponding with the extent of said seat-supporting member, whereby a table may be arranged in a different plane from that of said seat members, with the supporting members in one position, or the table and seat members may be arranged together in the same 20 plane so as to provide a bed or the like, with the supporting members in inverted position.

4. A knockdown table and seat comprising a plurality of duplicate straight unitary seat-supporting members of tubular form, a table-supporting inverted U-shaped member provided as a permanent part of each of said seat-supporting members, a T-connector member permanently connected to each end of each of said seat-supporting members and having upwardly and downwardly extending duplicate screw-threaded portions, an inverted T-shaped tubular leg adapted for removable screw-threaded engagement with either of said portions of the T-connector member which is extended downwardly, flat seat and table members, said seat members each having a hole at each end for engagement over said extending portions of said T-connector members when in upwardly extended position, screw-threaded means for removably securing said seat members to the upwardly extending portions, said seat and table members being of an aggregate width corresponding with the extent of said seat-supporting member, whereby a table may be arranged in an elevated plane from that of the seat members, when the supporting members occupy one position, or the table and seat members may be arranged together in the same plane so as to provide a bed or the like, when the supporting members occupy inverted position, and whereby said legs may be turned to occupy position entirely in the same plane as the supporting members so as to dispose each entire supporting structure in substantially flat and compact condition.

5. In a device of the class described, a pair of duplicate supporting members, a substantially inverted T-shaped leg having rotatably adjustable connection with each end of each of said supporting members so that each T-head may occupy position at ninety degrees to its support-

ing member for supporting the same or be turned to dispose each T-head in the plane of its supporting member for convenience in stacking into substantially flat condition, and a removable flat member adapted to be supported upon said supporting members.

6. A knockdown table and seat comprising a plurality of duplicate straight seat-supporting members, table-supporting members, means attaching said table-supporting members in parallel arrangement above said seat-supporting members, a substantially inverted T-shaped leg having rotatably adjustable connection with each end of each of said seat-supporting members so that the T-head may occupy position at 90 degrees to the seat-supporting member for supporting the same or be turned to dispose the T-head in the plane of the table and seat supporting members for convenience in stacking into substantially flat condition when the table and seat members are removed, and removable flat seat and table members.

7. In a knockdown structure of the class de-

scribed, a plurality of duplicate straight seat-supporting members of tubular form, a T-connector member attached to each end of each of said seat-supporting members and having upwardly and downwardly extending screw-threaded portions, an inverted T-shaped leg having screw-threaded connection with each of said downwardly extending portions so that the T-head may occupy position at 90 degrees to the seat-supporting members for supporting the same or be turned to dispose the T-head in the plane of the seat-supporting members so as to lie in substantially the same plane with said seat-supporting members, whereby said members may be stacked in substantially flat condition when the seat members are removed, flat seat members, said seat members having apertures to engage over said upwardly extending portions, and canopy-supporting means having screw-threaded engagement with said upwardly extending portions and having means for removably securing said seat members in place.

JOHN C. LA RUE.
